UNITED STATES PATENT OFFICE.

EDWARD CRABBE, OF SEATTLE, WASHINGTON.

INSULATED HANGER.

973,409.

Specification of Letters Patent. Patented Oct. 18, 1910.

Application filed February 19, 1910. Serial No. 514,732.

To all whom it may concern:

Be it known that I, EDWARD CRABBE, of Seattle, in the county of King and State of Washington, have invented certain new and useful Improvements in Insulated Hangers; and I do hereby declare the following to be a full, clear, and exact description of the invention, such as will enable others skilled in the art to which it appertains to make

10 and use the same.

In the stringing of electric conductors, such as telephone wires, etc., it has been customary to secure the conductor to a supporting member by means of a short piece 15 of wire or to twist the conducting wire around the support in order to insure its retention. This causes much annoyance because of the snapping of the wires at the binding point under the pressure of wind or 20 ice, there being insufficient play allowed the wires to withstand such weight.

It is the object of my invention to overcome this trouble and to this end I provide a hanger which while affording the necessary support for the wire will prevent strain 25 thereupon and one which may be turned in any desired direction relatively to its support without danger of twisting or crimping or otherwise injuring the wire.

30 In the accompanying drawings, Figure 1 is a view in perspective showing the support attached to the side of a wall. Fig. 2 shows the support adapted for a turn of the wire. Fig. 3 is a sectional view.

35 Referring to the drawings, 1 designates a block of insulating material, such as porcelain, and 2 a yoke, the spaced-apart ends of which are embedded in the block. In the periphery of the block a circumferential 1

40 groove 3 is formed to accommodate telegraph or telephone wires and prevent lateral

displacement thereof. The yoke spans the groove.

The hanger is attached to any suitable support by means of a hook 4 of peculiar 45 construction by means of which it may be so positioned as to allow wires to be strung at different angles without danger of undue twisting or crowding the blocks from their supports. The eye portion 6 of the screw 50 is in the form of an involute spiral, and is of such length as to provide considerable overlap. The space between the overlapping portions is sufficient to allow of the free passage of the yoke, and hence the 55 block may be readily secured to the eye and at the same time it can be turned on almost a complete circle, with the eye of the screw as a pivot. It may occupy a horizontal position, as shown in Figs. 1 and 3, or a vertical 60 position as indicated in Fig. 2.

I claim as my invention:

1. A hanger or support for electric wires comprising a block having a circumferential groove, a yoke projecting from said block 65 and spanning said groove, and a support having an involute spiral with which said yoke is designed to engage.

2. A hanger or support for electric wires comprising a block, circular in cross section, 70 having a circumferential groove, a yoke projecting from said block and spanning said groove, and a screw eye in the form of an involute spiral with which said yoke is designed to engage.

75 In testimony whereof, I have signed this specification in the presence of two subscribing witnesses.

EDWARD CRABBE.
